US00D579542S

(12) **United States Design Patent**
Ranalletta et al.

(10) **Patent No.:** **US D579,542 S**
(45) **Date of Patent:** **** Oct. 28, 2008**

(54) **MEDICAL LIQUID ADMINISTRATION DEVICE**

(75) Inventors: **Joseph Vince Ranalletta**, Englewood, CO (US); **Laura Zoerner**, Highlands Ranch, CO (US)

(73) Assignee: **Baxa Corporation**, Englewood, CO (US)

(**) Term: **14 Years**

(21) Appl. No.: **29/261,235**

(22) Filed: **Jun. 9, 2006**

(51) **LOC (8) Cl.** **24-01**

(52) **U.S. Cl.** **D24/108**

(58) **Field of Classification Search** **D24/108, D24/111, 107, 121, 118, 112, 130; 604/155, 604/54, 38, 135, 141, 214, 218, 152; 128/DIG. 1, 128/DIG. 12**

See application file for complete search history.

(57) **CLAIM**

The ornamental design for a medical liquid administration device, as shown and described.

DESCRIPTION

FIG. 1 is a perspective view of the medical liquid administration device;

FIG. 2 is a front view of the medical liquid administration device;

FIG. 3 is a back view of the medical liquid administration device;

FIG. 4 is a right end view of the medical liquid administration device;

FIG. 5 is a left end view of the medical liquid administration device;

FIG. 6 is a top view of the medical liquid administration device; and,

FIG. 7 is a bottom view of medical liquid administration device.

The broken lines in FIGS. 4 and 5 are included for the purpose of illustrating portions of the medical liquid administration device that form no part of the claim.

1 Claim, 4 Drawing Sheets
